MARY H. PHILLIPS, OF ST. LOUIS, MISSOURI, ASSIGNOR TO JULIUS H. WISE, OF
ST. LOUIS, MISSOURI

GUN PORT

Application filed August 24, 1931. Serial No. 558,886.

This invention relates to new and useful improvements in gun ports.

The objects of the present invention are to provide a gun port which is of simple construction and which is provided with a closure plate located on the outer side thereof and manually operable from the inner side whereby said gun port can be opened only from the interior of the booth or cage and whereby said closure plate when in closed position cannot be moved or pried open by a person located outside of said cage.

Other objects of the invention are to provide a gun port adapted to be secured within an opening formed in a bullet-proof wall and having a closure plate mounted on the outer side of said gun port and spring-held in closed position, said closure plate being so mounted that it can be moved forwardly to become unseated and then laterally to clear the opening formed in said gun port.

With these and other objects in view, my invention consists in certain novel features of construction and arrangement of parts, hereinafter more fully described and claimed, and illustrated in the accompanying drawing, in which—

Figure 1 is a front elevational view of my gun port attached in position.

30 Figure 2 is a rear elevational view of same.

Figure 3 is an enlarged vertical cross section taken on line 3-3 of Figure 1.

Figure 4 is a side elevational view of my gun port, partly in cross section, and showing the closure plate in open position.

Referring by numerals to the accompanying drawing, 10 indicates a bullet-proof wall in the present case formed of non-shatterable glass. This wall is provided with an opening 11 in which is arranged a gun port 12.

Briefly this gun port consists of an outer member 14, an inner member 15, a body portion 16, and a closure plate 17.

The outer member 14 and body portion 16 are formed integral, member 16 being of cylindrical shape and fitting loosely into the opening 11.

The outer member 14 is in the form of a flange which laps over the outer face A of wall 10. The inner member 15 is of ring

shape and fits against the inner side B of said wall and is secured to the inner end of body portion 16 by screws 17 which latter are screw-seated in the threaded bores 18 formed in said body portion.

Flange 14 and ring 15 are of substantially the same diameters and serve to clamp therebetween said wall 10, thereby securing the gun port in position within the opening 11. Preferably gaskets 19 of felt or other suitable material are interposed between said members and the wall 10 to form a more efficient clamp and seal.

The body portion 16 is formed with a central opening 20 which is preferably tapered forwardly. The rear end of this opening is aligned with the opening 21 formed by ring or inner member 15. The forward end of said opening 20 terminates in an outwardly flared seat 22 in which is adapted to be seated closure member or plate 14, the edge of which is tapered as indicated at 24 in order to form a snug fit.

This closure plate 14 is formed with an integral radial arm or extension 25 which is adapted to lie flat against the face of member 14 when said closure plate occupies closed position (see Fig. 3). A horizontally disposed bolt 26 is mounted in bore 27 formed in the upper portion of member 17 and the forward end of said bolt is reduced and screw-threaded as indicated at 28 and engages extension 25. The inner end 29 of said bolt is enlarged in diameter and has bearing in tubular extension 30 which projects from said body portion inwardly and outwardly through opening formed in ring or inner member 15. The bore 27 is of substantially the same diameter as the inner end 29 and is of larger diameter than the shank portion 90

26^a of said bolt. Thus an annular space is provided in which is received a coiled spring 31, one end of which bears against the outer end of said bore adjacent to flange 14 while the other end thereof bears against the shoulder 34 formed by the junction of the shank 26^a and the enlarged inner end 29. Thus the tension of said spring serves to hold the bolt in inward or retracted position, thereby holding the closure plate to its seat in the body 95 100

portion and closing the opening 20. A handle or thumb piece 35 is secured to end 28 and provides means whereby said bolt can be manually operated to open and close said closure plate.

5 The bolt 26 is slidably and revolvably mounted in position. When it is desired to open the gun port the bolt is pressed forwardly so as to unseat said closure plate whereupon said bolt is partially rotated to move said closure plate to one side clear of the opening 20. To close said opening said bolt is rotated to bring the closure plate in register with the seat 21, whereupon the tension of the spring seats the closure plate. The outer face of this closure plate is formed smooth and is devoid of any projections or recesses so that said closure plate cannot be forced open by means of tools applied to the outer face thereof.

10 The countersunk portion of the closure plate when closed prevents accidental displacement thereof. The coiled spring is of predetermined strength so that sufficient force has to be applied to the thumb member or wing nut 35 to unseat or move the plate beyond the plane of the seat before said closure plate can be moved laterally. As soon as the plate is moved in axial alignment with the seat the coiled spring automatically restores the plate in closed position.

15 I claim:

1. A gun port comprising a body portion adapted to be secured within an opening 35 formed in a wall and provided with a centrally disposed aperture establishing communication between the respective sides of said wall, a closure plate disposed adjacent to the outer side of said body portion for closing said aperture, and a bolt slidably and revolvably mounted in said body portion to one side of said aperture and having its outer end secured to said closure plate and having its inner end extending beyond the inner side 40 of said body portion, said bolt being manually operable slidably to seat and unseat said closure plate and revolvably to swing said closure plate relatively to said aperture.

2. A gun port comprising a body portion 50 adapted to be secured within an opening formed in a bullet-resistant wall and provided with a central aperture, the outer end of which terminates in an inwardly tapered seat, a closure plate arranged adjacent to the outer side of said body portion and having a tapering edge fitting into the tapered seat of said aperture, a bolt slidably and revolvably mounted in said body portion to one side of said aperture and having its outer end secured to said plate to permit displacement of said closure plate from said seat, and a handle secured to the inner projecting end of said bolt whereby said closure plate can be manually operated from the inner side of said gun 60 port into open and closed positions.

3. A gun port comprising a body portion adapted to be secured within an opening formed in a bullet-resistant wall and provided with a centrally disposed aperture, the outer end of said aperture terminating in an inwardly tapering seat, a closure plate arranged adjacent to the outer side of said body portion and having a tapering edge fitting into said tapering seat of said aperture, a bolt operatively mounted in said body portion to one side of said aperture and having its outer end secured to said plate, a handle secured to the inner end of said bolt, and a spring for yieldably holding said closure plate to its seat, said bolt being manually operable to unseat said closure plate and move it laterally to one side of said aperture.

4. A gun port comprising a body portion adapted to be secured within an opening of a bullet-resistant wall and provided with a central aperture, the outer end of said aperture terminating in an outwardly flared seat, a closure plate having an obliquely disposed edge adapted to fit in said seat, a bolt slidably and revolvably mounted in said body portion and having one end projecting outwardly and secured to said closure plate and having its opposite end extending inwardly and adapted to be manually operated, and a coiled spring engaging said bolt and said body portion to hold said closure plate to its seat, said bolt being slidable in one direction to unseat said closure plate and revolvably to move said closure plate to one side of said aperture.

5. In a gun port construction, the combination with a bullet-resistant wall provided with an opening, of a gun port member disposed within said opening and provided with an aperture extending therethrough, the outer end of said aperture terminating in an outwardly flared seat and the outer end of said gun port member being provided with a flange overlapping the outer side of said wall, a ring secured to the inner end of said member and overlapping the inner side of said wall whereby said member is held in position within said opening, a closure plate located adjacent to the outer side of said gun port member and having an obliquely disposed edge to fit into the seat of said member, and a mounting in said gun port member for supporting said closure plate, said mounting being manually operable to unseat said closure plate and move it laterally to one side of said aperture.

6. In a gun port construction, the combination with a bullet-resistant wall provided with an opening, of a gun port member disposed within said opening and provided with an aperture extending therethrough, the outer end of said aperture terminating in an outwardly flared seat and the outer end of said gun port member being provided with a flange overlapping the outer side of said wall, a ring secured to the inner end of said

member and overlapping the inner side of said wall whereby said member is held in position within said opening, a closure plate located adjacent to the outer side of said 5 gun port member and having an obliquely disposed edge to fit into the seat of said member, a mounting in said gun port member for supporting said closure plate, said mounting being manually operable to unseat said 10 closure plate and move it laterally to one side of said aperture, and a spring cooperating with said mounting for yieldably holding said closure plate to its seat.

7. In a gun port construction, the combination with a bullet-resistant wall provided 15 with an opening, of an aperture gun port member disposed within said opening and having terminal flanges overlapping the ends of said opening, a closure plate closing the outer end of the aperture of said member, 20 said end being provided with a seat to receive said plate in countersunk position, a bolt slidably and revolvably mounted in said member and having its outer end secured to said 25 closure plate and having its inner end projecting from said member, a wing nut secured to said inner end to permit manual operation of said bolt and said closure plate, and a coiled spring associated with said bolt 30 and for holding said closure plate to its seat, said bolt being operable slidably to unseat said plate and revolvably to move it laterally relatively to said seat.

In testimony whereof I hereunto affix my 35 signature this 15th day of August, 1931.

MARY H. PHILLIPS.
